UNITED STATES PATENT OFFICE.

HARRY J. PENN, OF MADISON, NORTH CAROLINA.

SUSPENDER.

Application filed October 27, 1922. Serial No. 597,329.

The device forming the subject matter of this application is a pair of suspenders, of that general type in which an inner loop is mounted slidably within an outer loop or holder, the inner loop carrying compression springs, which, coacting with the outer loop, afford the desired resiliency.

The invention aims to provide novel cushion members, which, being carried by the inner loop, cooperate with the outer loop or holder to accomplish results which will be set forth in detail hereinafter.

Another object of the invention is to provide novel means whereby the effective length of the suspender strap may be adjusted.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the invention, parts being broken away; Figure 2 is a section on the line 2—2 of Figure 1; Figure 3 is a section on the line 3—3 of Figure 1.

The device forming the subject matter of this application includes a holder or outer loop, denoted by the numeral 1, and made of flexible material. In the lower end of the holder 1 guides 2, in the form of eyes are mounted. The guides 2 may be made of metal or any other suitable material. The numeral 3 designates an inner loop, sometimes made of cord, and located partly within the holder 1. A spacer 4, which is rigid, is located within the holder 1 and is provided at its ends with eyes 5 which rest on the guides 2, the end portions of the inner loop 3 passing downwardly through the eyes 5 and through the guides 2, the ends of the inner loop 3 being joined, if desired, externally of the holder 1, by a coupling 6 carrying a hook 7 wherein a flexible element 8 is slidable longitudinally, the flexible element being equipped in its ends with open-

ings 9 adapted to be engaged with the suspender buttons of a pair of breeches. Tubular cushions are provided and there may be as many or as few of these cushions as is considered expedient. In the form selected as a material embodiment of the invention, a pair of lower cushions 10 is shown, the same resting on the eye 5 of the spacer 4, the numeral 11 making an upper cushion of tubular form, located within the holder 1, the inner loop 3 passing through all of the cushions. Any desired material may be used in the making of the cushions 10 and 11 but short pieces of ordinary rubber tubing will suffice. The cushions 10 and 11 may have a rotary movement on the inner loop 3. Compression springs 12 surround the inner loop 3, within the holder 1 and abut at their upper ends against the cushion 11, the lower ends of the springs abutting against the cushions 10, the springs being housed within the outer loop or holder 1.

The device as thus far described may be employed either on the front of a pair of suspenders, or on the rear thereof. But, wherever used, it is to be noted that the diameter of the cushions 10 and 11 is greater than the diameter of the springs 12. Consequently, when the device is in use, the cushions 10 and 11 act as spacers, preventing the outer loop of holder 1 from rubbing on the springs 12, when the inner loop 3 reciprocates within the outer loop or holder 1. The cushions serve to make the suspenders comfortable to the wearer, in that, owing to their resiliency, they prevent either the inner loop 3, or the springs 12 which surround it, from being thrust against the body of the wearer, the side portions of the holder or outer loop 1 intervening. The cushions lengthen the life of the inner loop 3 since, in a device of the class described, there is a constant friction between the end portions of the springs 12 and the inner loop or member 3, if the cushions are not used. In the absence of the cushion 11, the upper ends of the compression springs 12 tend to become entangled, notably after the suspenders have been in use for a considerable period of time, and, when the upper ends of the springs 12 become entangled, the extremities of the springs generally project outwardly, wearing or tearing the holder 1. Often, when the ends of the springs project, as above stated, they penetrate the holder 1 and prick and annoy the

wearer. The lower cushions 10 tend to preserve the inner loop 3, especially in combination with the spacer 4. Much that has been stated hereinbefore relative to the upper cushions 11 applies to the lower cushions 10, these elements preventing the ends of the springs 12 from piercing the holder 1 to the damage of the holder and to the discomfort of the wearer. If the upper cushion 11 is omitted, there is an undesirable clicking sound produced, when the suspenders are in use, due to the engagement between the upper ends of the compression springs 12.

The invention contemplates the provision of a novel means whereby the length of the suspenders may be increased or diminished at will. Having this consideration in mind, a link 14 may be mounted in the upper end of the outer loop or holder 1 and through this link, the suspender strap 15 passes slidably, the strap being supplied with eyelets 16 forming openings in the strap. Along the rear surface of the strap 15 passes a protecting strip 17, generally made of flexible material which is stitched at 18 to the strap. One end of the strap 15 is attached to a slide 19, in the form of a loop, through which the strap passes slidably, the slide 19 being provided with a hook 20 adapted

to be engaged with any of the eyelets 16, 30 to effect an adjustment, the nature of which will be obvious when Figures 1 and 2 of the drawings are noted. The strip 17 serves to prevent the hook 20 from wearing the shirt or other garment with which the suspenders are engaged. Again, the strip 17 takes the wear imposed by the link 14, and prevents the link from coming into direct contact with the strap 15.

Having thus described the invention, what 40 is claimed is:—

In a pair of suspenders, a loop-shaped holder, a loop slidable in the holder, compression springs receiving the loop, independent resilient tubular members mounted 45 on the loop and interposed wholly between the lower ends of the springs and the lower portion of the holder, and a resilient tubular member mounted on the loop and interposed between the upper ends of the springs, all 50 of said tubular members being of such diameter that by them the holder is spaced from the springs.

In testimony that I claim the foregoing as my own, I have hereto affixed my signature.

HARRY J. PENN.
